UNITED STATES PATENT OFFICE.

CHARLES COTTA, OF SHANNON, ILLINOIS.

AUTOMOBILE.

SPECIFICATION forming part of Letters Patent No. 700,175, dated May 20, 1902.

Application filed October 6, 1900. Serial No. 32,111. (No model.)

To all whom it may concern:

Be it known that I, CHARLES COTTA, a citizen of the United States of America, residing at Shannon, in the county of Carroll and State 5 of Illinois, have invented certain new and useful Improvements in Automobiles, of which the following is a specification.

My invention relates to certain improvements in automobiles, and has to do particu- 10 larly with the running-gear, the devices for transmitting the power from the motor thereto, and the devices for steering and controlling the vehicle.

To such end the invention consists in various 15 novel characteristics, the nature of which will appear from the description of a complete machine, and the essential features will be pointed out in the claims.

In the drawings, Figure 1 is a side elevation 20 of a complete vehicle with a portion of the body cut away to reveal parts within the same. Fig. 2 is a plan of the running-gear. Fig. 3 is a transverse vertical section in line 3 3 of Fig. 2 looking in the direction of the arrow 25 3. Fig. 4 is a transverse vertical section in line 4 4 of Fig. 2 looking in the direction of the arrow 4 in said Fig. 2. Fig. 5 is a longitudinal vertical section taken in the line 5 5 of Fig. 4 looking in the direction of the arrow 30 5 of said figure. Fig. 6 is a skeleton side elevation of the steering devices and other portions connected therewith. Fig. 7 is a detail vertical longitudinal section in line 7 7 of Fig. 2. Fig. 8 is a detail horizontal section 35 in line 8 8 of Fig. 7. Fig. 9 is a vertical transverse section in line 9 9 of Fig. 2. Fig. 10 is a section in line 10 10 of Fig. 9 looking in the direction of the arrow 10, and Fig. 11 is a section in line 11 11 of Fig. 10.

Referring to the drawings, A represents the body of the vehicle; B B' B² B³, the wheels; C, the frame of the running-gear, consisting of axles c c' c² c³, Fig. 2, upon which are bearing-blocks c⁴ c⁵ c⁶ c⁷, supporting the springs D, 45 which carry the body. The middle portions of the axles are made in the form of a loop c⁸ c⁹, and a preferably double reach E is connected to the opposite ends of the rear axle and has projecting from its forward middle portion a spindle e, pivoted in the middle por-

tion e' of the loop c⁸, giving the front axle freedom to oscillate vertically upon this spindle. Upon the end of each axle is secured a collar F, from the top and bottom of which project two diverging arms f f', in which are threaded cones f² f³, upon which is pivoted an oscillating ring G, containing cups g g', adapted, together with the cones, to provide races for antifriction-balls g². The outer surface of the edges of the oscillating ring 60 are provided with cones g³ g⁴, and a hub H is provided with cups h h', between which and the cones g³ g⁴ are embraced antifriction-balls h² h³. This bearing gives the hub a free rotary movement about the oscillating ring and 65 also freedom of oscillation, together with the ring, upon a vertical pivot substantially central and diametrical with respect to the hub. From the oscillating ring G extends a curved arm g⁵, connected with the steering apparatus, 70 as will be described hereinafter, and from the outer edge of the hub extends an inwardly-curved web h⁵, terminating in two ears h⁶ h⁷, perforated at h⁸ h⁹, which are connected to a driving-shaft I by means of universal joints. 75 The shaft is journaled in the axle, which is preferably hollow, by means of bearings, and has upon its hub end a collar I', forked to afford two projecting arms or ears I² I³, disposed at right angles to those of the hub. A 80 pivot-block J is pivoted both to the collar and to the hub. Said block is provided with a series of radial channels J' and a central stud J². A washer J³ is provided with corresponding channels and is secured to the block by 85 means of a nut J⁴. In the sockets made by the two channels are held pivot-pins J⁵ J⁶, the pivot-pins J⁵ entering the hub and the pivot-pins J⁶ entering the collar on the shaft. The pivot-pins themselves are perforated to 90 receive pins J⁷, which fit into sockets J⁸ in the block and J⁹ in the washer to prevent the withdrawal of the pins from the sockets. The collar is shown as secured to the ends of the shaft by means of a pin I⁴. On the inner end 95 of each one of the axles is secured a sprocket-wheel I⁵, all four sprocket-wheels being geared by means of chains K to sprockets M M' M² M³ upon a main driving-shaft M⁴, journaled in brackets M⁵, secured to the body be- 100

low the bottom of the latter. The sprocket-wheels are loose upon the main driving-shaft, and the opposite ends of the latter have fastened upon it two brake-wheels $N N'$, the brake-wheel N being between the sprocket-wheels $M M'$ and the brake-wheel N' being between the sprocket-wheels $M^2 M^3$. Each brake-wheel carries three bevel-pinions $n n' n^2$, journaled radially with respect to the wheel and meshing with bevel-gears m upon the adjacent faces of the sprocket-wheels. Said brake-wheels also have comparatively wide rims n^3 , with outwardly-projecting side flanges $n^4 n^5$, between which is embraced a brake-strap N^2 , to be referred to later. The main shaft M^4 is divided in the middle to form end portions $m' m^2$ and carries upon opposite sides of the dividing plane two fast bevel-gears $M^6 M^7$, between which is arranged a loose sprocket-wheel N^3 . Said sprocket-wheel carries three radially-journaled bevel-pinions n^6 , in mesh with the bevel-gears $M^6 M^7$, and is adapted for attachment to a suitable motor.

Turning to the curved arm g^5 upon the oscillating rings G , said arms on the front axle are connected by a cross-rod O and those upon the rear axle by a cross-rod O' , the middle portion of each of the said rods being provided with a gudgeon o , upon which is pivoted one end of a link O^3 , the other end of which is pivoted to a depending arm o' , secured to a rock-shaft O^4 , pivoted in brackets $o^2 o^3$, secured to the body of the vehicle. Upon the intermediate portion of the rock-shaft is secured an upwardly-projecting arm o^4 , and on one side of said arm the shaft is divided at o^5 and the adjacent ends pivoted in brackets o^3 . Between said brackets the portion of the shaft indicated by the letter O^6 has fastened upon its end a disk o^8 , perforated to receive pins $o^6 o^7$, secured in a sliding collar o^8 , feathered to the portion of the shaft marked O^6 . On the end of the portion O^6 of the shaft is fastened a disk o^9 , also perforated to receive the pins $o^6 o^7$. These pins lock the two portions of the shaft together, and the sliding collar is provided with another pin o^a , adapted to enter a hole o^b in the bracket o^3 to lock the portion O^6 of the shaft to the body. When thus locked, the two wheels to which this portion is connected are fixed, as upon a rigid axle, and the guiding of the vehicle is effected by the wheels at the other end of the said vehicle.

Returning to the vertical arm o^4 on the rock-shaft, the same is connected, by means of a link p , with a horizontally-swinging arm p' , secured to an upright hollow post p^2 , journaled in bearings $p^3 p^4$, secured to the body and connected, by means of an oblique brace p^5 , with a horizontal extension p^6 at the upper end, which terminates in a vertical fork, composed of the upper branch p^7 and the lower branch p^8 . In the lower arm of the fork is pivoted the lower end of a lever p^9 , provided at its upper end with a handle P and below

the handle with a detent p^a , engaging teeth p^b upon the upper arm p^7 of the fork. A handle P' provides means for disengaging the detent, and a spring p^c , confined between the detent-handle and the lever-handle, tends to keep the detent in engagement with the teeth. The upper arm p^7 of the fork is curved to form a segment, the center of which is at the pivotal point of the lever. To the lever, between the handle and the pivot, is pivoted a sliding rod q , the other end of which is pivoted to one end of the head of a T-shaped lever q' , the shank q^2 of which is pivoted to the brace p^5 , and the other end of the head of which is pivoted to a vertically-sliding rod q^3 , said rod being pivoted at its lower end to a vertically-oscillating brake-lever q^4 , a spring q^5 , confined between the end of the brake-lever and a nut q^6 , cushioning the upward pull of the rod upon the brake-lever. The brake-lever is forked to provide two arms $q^7 q^8$, pivoted between their ends respectively to brackets $q^9 q^{10}$, secured to the brackets M^5 . A rod q^b connects the ends of the fork, and the brake-straps N^2 are secured to this bar, extend around the brake-wheels, and have their other ends fastened to blocks q^c , also supported by the brackets M^5 , carrying the main driving-shaft. The upward pull of the vertically-sliding rod caused by the movement of the handle P away from the vertical post tightens the brake-strap upon the brake-wheel, and the reverse movement loosens it up sufficiently to release the brake. The horizontal oscillation of the handle P turns the wheels of the vehicle to guide the same, so that both the guiding and stopping of the vehicle are effected through the same device. Upon the vertically-sliding rod q^3 is secured a collar, to which is fastened a vertical rod q^d , pivoted at its upper end to the handle r of a valve R , which represents the controlling device for the motor, whatever the latter may be, said controlling device being operated by the vertical movement of the rod which operates the brake and being so adjusted as to shut off the power prior to the application of the brake and turn it on subsequent to the release of the latter.

Looking at Figs. 1, 2, and 3, downwardly-projecting studs S will be seen secured to the loop-shaped portions of the axle, which have pivoted upon their lower ends vertically-oscillating spring-arms T , carrying two idle sprockets $t t'$, the sprocket t being journaled in the end of the arm and resting upon the top of the upper chain, and the sprocket t' being journaled in the middle portion of the arm and bearing upon the under side of the lower portion of the chain. The distance between the two sprockets is so proportioned to the other parts that the spring-arm is bent and tends to draw the two portions of the chain together in its effort to straighten itself. This device is intended to take up any slack

in the chain due to the vertical movement of the body upon the running-gear or to any other cause.

The invention is not limited to the exact details of construction described, inasmuch as more or less variation is possible without departing from the essential features thereof.

I claim as new and desire to secure by Letters Patent—

- 10 1. In a vehicle, the combination with a suitable running-gear, of an axle, a bearing-ring vertically pivoted upon the axle, a wheel journaled upon the bearing-ring and having a portion extending within the same, a driving-shaft and a universal joint connecting the driving-shaft to the hub within the ring concentric with the wheel and substantially in the pivotal axis of the ring; substantially as described.
- 15 2. The combination with an axle, a bearing-ring diametrically pivoted to the axle, the hub, H journaled upon the bearing-ring, and having the inwardly-curved web, h^5 , the shaft, I, journaled in the axle and having the forked collar, I', and the bearing-block, J, in the pivotal axis of the ring and the center of the hub, said block being provided with pivot-pins pivoted to the hub and collar respectively at right angles to each other, with a washer for clamping said pins in place and means for securing the washer tightly upon said pins; substantially as described.
- 20 3. The combination, in a four-wheeled vehicle, of a suitable framework, front and rear wheels, devices for turning both front and rear wheels with relation to the framework to steer the vehicle and means for disengaging one set of wheels from the steering devices and engaging them with other por-

tions of the vehicle, so as to prevent their oscillation with respect to the vehicle; substantially as described.

4. In a vehicle, the combination with the body, and front and rear wheels, adapted to be operated to steer the vehicle, of the rock-shaft, O⁴, connected at its respective ends to the front and rear wheels and provided with a clutch adapted to engage that portion of the shaft which is connected to one set of wheels, alternately with the other portion and with the vehicle and steering devices connected with said other portion and adapted to rock the shaft; substantially as described.

5. In a driving-gear for a four-wheeled vehicle, the combination with a divided driving-shaft, of a loose driving-wheel at the point of division, radially-journaled pinions in said driving-wheels, gears secured to the two portions of the shaft and meshing with said pinions, brake-wheels upon the respective portions of the shaft containing radial pinions, loose gears upon the opposite sides of said brake-wheels, meshing with the pinions in the latter, suitable connections between said loose gears and the respective four-wheels of the vehicle and suitable brakes applied to the brake-wheels; substantially as described.

In witness whereof I have hereunto set my hand, at Shannon, in the county of Carroll and State of Illinois, this 27th day of September, A. D. 1900.

CHARLES COTTA.

Witnesses:

GEORGE T. SHERWOOD,
CHARLES SPATZ.
